UNITED STATES PATENT OFFICE.

JOSEPH STASINSKI, OF PHILADELPHIA, PENNSYLVANIA.

SAFETY-VALVE FOR WATER-TUBE BOILERS.

1,356,836.

Specification of Letters Patent. Patented Oct. 26, 1920.

Application filed February 15, 1919. Serial No. 277,185.

To all whom it may concern:

Be it known that I, JOSEPH STASINSKI, a citizen of the United States, residing in Philadelphia, Pennsylvania, have invented 5 certain Improvements in Safety-Valves for Water-Tube Boilers, of which the following is a specification.

My invention consists of a special form of valve intended to prevent the escape of 10 steam or water, under pressure, from the tube structure of a water tube boiler in case of leakage or like defect in the tube structure of such a boiler.

My invention is illustrated in the accompanying drawings, in which—

Figure 1 is a view, partly in side elevation and partly in section, of sufficient of a water tube boiler of the type to which my invention relates, as to illustrate said invention;

Fig. 2 is a horizontal sectional view, on a larger scale, of the valve structure constituting the subject of my invention;

Fig. 3 is a view, partly in side elevation and partly in vertical section, showing said valve structure in open relation to the pipe with which it coöperates, and

Fig. 4 is a view similar to Fig. 3, but showing the valve in closed relation to said pipe.

In Fig. 1 of the drawing, 1 represents the water tube structure of the boiler, 2 the opposite headers of the same, 3 the steam drum, 4 a pipe or nipple connecting said steam drum with the rear header of said 30 tube structure, and 5 the pipe connecting said steam drum with the forward header of the tube structure, all of these parts being common to water tube boilers as now constructed.

In the event of any defect in the tube structure which would permit of the escape of water or steam therefrom, under pressure, such escaping water or steam is liable to blow the ignited fuel from the fire box and 45 numerous fatalities have resulted from this cause, hence various forms of valve mechanism have been devised for closing communication between the tube structure and the steam drum when the pressure in the 50 tube structure has, by reason of leakage, been reduced below that in the drum, and my invention comprises a special form of valve mechanism for this purpose.

The valve is shown as applied to the upper 55 end of the pipe or nipple 4 which extends from the rear header 2 of the tube structure

to the steam drum 3, the upper end of said pipe projecting into the drum and constituting the seat for the valve.

Bearing upon the inner side of the shell of the drum 3 is a plate 6 which is secured in place by the same nut 7 which secures the pipe 4 on the inside of the drum, said plate having radiating wings 6^a from each of which projects upwardly a post 8 whereby said posts can be secured in their proper position within the drum without the necessity of forming openings in the shell of the latter for their reception.

A valve 9, which coöperates with the valve seat at the inner end of the pipe 4 has wings 10, each of which has at its outer end a sleeve 10^a surrounding one of the posts 8, the valve being thereby guided in its vertical movements and said posts also serving to aid the usual projecting guide fingers on the valve in preventing lateral displacement of said valve in respect to the valve seat.

Any desired yielding means may be employed for the purpose of normally maintaining the valve in equilibrium above the valve seat and in open relation thereto, the means which I illustrate being as follows: Surrounding each post 8 above and below the wings 10 are spiral springs 11 which tend to maintain the valve in proper position, as shown in Fig. 3, but as soon as there is any reduction in pressure within the pipe 4, due to leakage from the tube structure or other cause the valve 9 will be drawn down to its seat on the inner end of the pipe, as shown in Fig. 4, and will prevent further escape of steam or water into said pipe from the drum 3, the valve remaining in this closed position as long as the cause continues.

The wings of the valve are stiffened by ribs 10^b on the backs of the same, and the posts 8 are threaded at their upper ends for the reception of nuts 12, by the adjustment of which the tension of the springs 11 can 90 be regulated, as may be desired.

The valve 9 has, projecting from the back of the same, a central stud 13 whereby it may be secured in the chuck of a lathe used for truing up the face of the valve which 100 contacts with the seat.

While I prefer to secure the plate 6 to the shell of the drum by the same nut which secures the pipe 4 thereto this is not essential to the main feature of my invention, which consists in making the post carrying plate 6 separate from the shell of the drum

3 and from the valve seat, so as to render unnecessary the formation of openings in said shell for securing the posts in position therein and also for rendering unnecessary 5 the increase in size of the valve seat to correspond with the length of the guide arms on the valve, and while I also prefer to dispose the springs 11 so as to surround the posts 8 said springs may be otherwise disposed, if desired, and the springs above the 10 wings 10 may also be dispensed with when it is not desired to hold the open valve in equilibrium above its seat.

The valve structure which I have devised 15 may be used in connection with either of the pipe connections 4 or 5.

I claim:

1. The combination of a tube structure and steam drum of a water tube boiler, a 20 pipe connecting said drum with one of the headers of the tube structure, a valve seat on the inside of the drum communicating with said pipe, a valve adapted to close against said seat when the pressure within 25 the drum exceeds that in the tube structure or its connections, guide wings projecting from said valve, a plate separate from the shell of the drum but disposed within the same, said plate having inwardly projecting 30 posts which serve as guides for the project-

ing wings of the valve, and yielding means for normally retaining said valve in open relation to its seat.

2. The combination of the tube structure and steam drum of a water tube boiler, a 35 pipe connecting said drum with one of the headers of the tube structure and projecting into said drum, a valve seat on the inside of the drum communicating with said pipe, a valve adapted to said seat, a plate disposed within the drum and having inwardly projecting valve-guiding posts, and a nut applied to the inwardly projecting portion of said pipe and serving to confine both pipe and plate to the shell of the drum. 40

3. The combination of the tube structure and steam drum of a water tube boiler, a pipe connecting said drum with one of the headers of the tube structure, a valve seat on the inside of the drum communicating with 50 said pipe, a plate disposed within the drum and having inwardly projecting posts, and a valve adapted to close upon said seat, said valve having guide members engaging said posts and also having, on its back, a central 55 projecting stud.

In testimony whereof I have signed my name to this specification.

JOSEPH STASINSKI.
